Inventor
Cornelius W. Simpson

United States Patent Office.

CORELLI W. SIMPSON. OF BANGOR, MAINE.

Letters Patent No. 102,167, dated April 19, 1870.

IMPROVED DEVICE FOR HANGING PICTURES, &c.

The Schedule referred to in these Letters Patent and making part of the same.

To all whom it may concern:

Be it known that I, CORELLI W. SIMPSON, of Bangor, in the county of Penobscot and State of Maine, have invented new and useful Improvements in Hanging Picture and Mirror-Frames; and I do hereby declare that the following, taken in connection with the drawings which accompany and form part of this specification, is a description of my invention, sufficient to enable those skilled in the art to which it appertains to practice it.

This invention relates to improved appliances by which picture and mirror-frames are suspended from the house-walls; and

The invention consists in constructing the books with open instead of closed eyes, for the reception of the cord.

Also, in a cord-holder, which is attached to the nail in the wall; and

Also, in a clasp which secures the ends of the cord behind the frame.

Figure 1 shows in perspective a picture-frame, with my improvements suspending the same;

Figure 2 is a perspective view of the clasp opened;

Figure 3 is a horizontal section of the cord-holder, taken on line *x y*, fig. 1;

Figure 4 is a perspective view of the hook;

Figure 5 is a vertical longitudinal section of the cord-holder in a modified form; and

Figure 6 is also a longitudinal vertical section of the cord-holder, in still another modified form of construction.

Similar letters of reference indicate corresponding parts in the several figures.

In the drawings—

A represents the frame, and

B, the cord.

d d are screw-hooks, which are formed open instead of closed, in the usual manner, so that the cord can be inserted in or removed from the hooks without unfastening the ends of the cord.

a is a clasp formed in two halves, and hinged at one side, as shown.

Serrated apertures are formed in each end, for the insertion of the ends of cord *B*, when, by closing the clasp and placing the rings *c c* upon the ends of the

clasp, it is securely locked, thereby virtually uniting the ends of the cord without an unsightly knot, yet in such manner as to allow their instant release if necessary.

C is the cord-holder which is shown in fig. 1, formed with a ring at the top, for suspending it upon nail *b*.

It has also two holes in the lower end for the cord, as is shown in fig. 3.

The holder being formed concave upon the back side, the cord can either be passed through and the ends united behind the frame, as shown, or the ends may be knotted in the cavity behind the holder if desired.

In fig. 5 the holder *C* is shown with the nail *b* formed upon or rigidly attached as part of the same, while in fig. 6, instead of the ring, the holder is formed to attach to the nail in such manner that the nail is hidden from view by the holder.

It will be apparent that by this method of hanging pictures they can be instantly taken down, without the difficulty of unhooking the cord from the nail, which, being near the ceiling, is not easily accessible, for the hooks *d d* can be readily released from the cord, when the latter, relieved from the weight it held, can be taken down if desired.

The holder *C* prevents the cord from wearing upon nail *b*. It facilitates hanging therefrom, and as it admits of great variety of design, may be rendered an additional ornament as well as an article of utility.

The use and utility of clasp *a*, in connection with picture-hanging, has already been explained, and for a great variety of other purposes it is equally effective.

Having thus described my invention,

What I claim as new, and desire to secure by Letters Patent, is—

1. The hinged cord-holder or clasp *a*, with its rings *c c*, constructed as shown.

2. In combination with the hinged clasp *a*, the suspending cord-holder *C* and nail or hook *d*, constructed as shown and described.

CORELLI W. SIMPSON.
